PORTRABLE PHONOGRAPH OR SIMILAR ARTICLE

James T. Asaki, Batavia, N.Y., assignor to Sylvania Electric Products Inc., a corporation of Delaware

Filed Nov. 6, 1964, Ser. No. 82,499

Term of patent 7 years

(Cl. D56—4)

Fig. 1

Fig. 2

Fig. 3

Fig. 4

Fig. 5

FIG. 1 is a front perspective view of a portable phonograph embodying my new design and showing the record player in the operational position;

FIG. 2 is a rear three-quarters perspective view on a reduced scale of the phonograph showing the record player in the operational position and the loudspeakers in the storage and transporting position and partially disposed within the rear portion of the cabinet;

FIG. 3 is a rear three-quarters perspective view on a reduced scale of the phonograph showing the record player in the operational position and the rear portion of the cabinet with the loudspeakers removed from the storage and transporting position;

FIG. 4 is a side elevational view on a reduced scale of the phonograph showing the contour thereof with the record player and the loudspeakers in the storage and transporting position; and

FIG. 5 is a front elevational view on a reduced scale of the phonograph, with the record player in the storage and transporting position.

The dominant features of the design reside in the portions shown in full lines.

I claim:

The ornamental design for a portable phonograph or similar article, substantially as shown and described.
